UNITED STATES PATENT OFFICE.

JAMES B. HASKELL, FERDINAND BRUESKE, AND CHARLES CLYDE PALMER, OF MINNEAPOLIS, MINNESOTA, ASSIGNORS TO CROSBY AUTOMATIC DOOR COMPANY, OF MINNEAPOLIS, MINNESOTA, A CORPORATION OF MINNESOTA.

AUTOMATIC DOOR-OPENER.

1,323,529.

Specification of Letters Patent.

Patented Dec. 2, 1919.

Application filed March 22, 1918. Serial No. 224,060.

To all whom it may concern:

Be it known that we, JAMES B. HASKELL, FERDINAND BRUESKE, and CHARLES CLYDE PALMER, citizens of the United States, residing at Minneapolis, in the county of Hennepin and State of Minnesota, have invented certain new and useful Improvements in Automatic Door-Openers; and we do hereby declare the following to be a full, clear, and 10 exact description of the invention, such as will enable others skilled in the art to which it appertains to make and use the same.

Our invention has for its object to provide a simple and highly efficient automatic door actuating mechanism, the term "door" being herein used in such a broad and liberal sense as to include gates or other devices that are movable to open and close passageways. The actuating mechanism, however, is especially well adapted for use in connection with garage doors, and in the accompanying drawings is illustrated as applied for such purpose. In garages, compressed air for various purposes, such as charging tires, is always available, and hence, we utilize compressed air as a power medium for operating the door. A cylinder and reciprocating piston is provided with suitable connections to the door for raising and lowering the same; a suitable valve mechanism is provided for controlling admission of air to and discharge from such cylinder, and weight actuated tripping devices are installed in the roadway at opposite sides, to wit, at the inside and 35 at the outside of the door; and are provided with connections for operating the valve mechanism.

These so-called tripping devices, *per se*, are of novel construction, and the manner of 40 their connection to the valve mechanism, also involves important novel features.

There is also provided a novel semaphore or signal device for indicating that the door has been released for closing movement; and 45 this semaphore, as a novel feature, is arranged to be actuated by the exhaust air from the door operating engine.

The invention, in its preferred form, is 50 illustrated in the accompanying drawings wherein like characters indicate like parts throughout the several views.

Referring to the drawings:

Figure 1 is an elevation with some parts

sectioned, illustrating the invention applied to the door of a garage, or the like;

55

Fig. 2 is a plan view of the tripping devices and their connections to the valve mechanism;

60

Fig. 3 is a bottom plan view of one of the tripping devices;

65

Fig. 4 is a vertical section taken through one of the tripping devices on the line 4—4 of Fig. 2, the parts being shown on the same scale as in Fig. 3;

70

Fig. 5 is a vertical section taken approximately on the line 5—5 of Fig. 2, the parts being shown on the same scale as in Figs. 3 and 4;

75

Fig. 6 is a detail view showing a portion of the connection between the left hand tripping device and the controlling valve, some parts being in vertical section and the parts being shown on a much larger scale than in Fig. 3;

80

Fig. 7 is a front elevation of the semaphore;

85

Fig. 8 is a side elevation thereof; and

Fig. 9 is a plan view of the controller valve, the top plate thereof removed.

The numeral 10 indicates the road bed and 80 the numeral 11 the ceiling or overhead structure, and the numeral 12, vertical posts at the door opening of the garage, or the like.

The numeral 13 indicates the door, this door, as shown, is of simple form and by 85 means of brackets 14, is mounted to slide vertically on the posts 12, but it will be understood that so far as this invention is concerned, the door may take various forms and may be mounted in various different ways 90 for its opening and closing movements.

In Fig. 1, the door opening is indicated by the dotted lines 15. The weight of the door is nearly, but not quite, counterbalanced by a weight 16 attached to cables 17 95 that run over guide sheaves 18 and are attached to the opposite corners of the door. The sheaves 18 are journaled to brackets 19 suitably supported on the wall of the building.

100

The air engine for lifting the door comprises a cylinder 20 which may be secured in any suitable position, but as shown, is secured to the ceiling above the door opening. Working in this cylinder 20 is an ordinary 105 piston, the stem 21 of which projects and is

equipped with one or more grooved sheaves 22. Journalized in lugs projected from the compression end of the cylinder 20 is one or more guide sheaves 23. The door lifting cable 24 is attached to the central upper edge portion of the door and is passed one or more times around the sheaves 22 and 23 and has its end anchored at 25 to a fixed part, such as the front end of the cylinder 20. Obviously, when air is admitted into the end of the cylinder 20, and piston moved outward, sheave 22 will be moved away from sheave 23 and the cable 24 will be taken up with a multiplied motion, thereby lifting the door from lowered to completely open position with a comparatively short piston travel. Such arrangements are well understood and need not be further here considered.

Air for operating the above described door lifting engine will be supplied from a suitable source, such as a storage tank, not shown, through pipes 26 and 27, the delivery end of which latter pipe leads to the compression end of the cylinder 20. The two pipes 26 and 27 are connected to the controller valve. This controller valve is preferably located in a pit or sunken housing 29^a located below the floor surface of the door opening. The controller valve may be of any well known or suitable type, but, as shown, it comprises a valve casing 29 into which the pipes 26 and 27 open, respectively, through ports 26^a and 27^a. An exhaust pipe 28 leads from a port 28^a in casing 29. Port 26^a is normally closed by a check valve 30 that is subject to a coiled spring 30^a. The port 28^a is normally closed by a check valve 31 that is subject to a light coiled spring 32. The stem of valve 31 is extended through a head 33 and is provided with nuts 34 at the back of said head. The head 33 is pivoted to an arm 35 of an oscillatory stem 36. This stem 36 extends upward through a stuffing box or other closed connection in the top plate of the casing 29, and to the upper end thereof, a double-ended lever 37 is intermediately secured, (see Figs. 1 and 2).

In Fig. 2, the position of the door is indicated by the dotted line marked 13^a. Located within the building or at the inner side of the door is a tripping device and located outside of the building or on the outer side of the door is a similar tripping device, both of which tripping devices are located in the driveway in position to be run over by the wheels of a vehicle that is being run into or out of the building through the doorway. These tripping devices involve important novel construction, and as preferably designed and shown, each comprises as follows:

Set into the driveway with its main body portion flush with the same is a metal bed plate 38 preferably a casting provided at

its ends with upwardly arched pockets 39 that are open at their bottoms, and in their opposing inner walls, are formed with downwardly diverging V-shaped cam slots 40. Trip rods 41 extend in elevated positions over the bed plates 38, and their ends are extended into the pockets 39 through the cam slots 40.

Located within the pockets 39 and rigidly secured at their upper ends to the inner ends of the trip rod 41 are depending arms 42, the lower ends of which are pivotally connected by pins 43 to cross heads 44 mounted to move vertically in depending guide brackets 45, which, as shown, are cast integral with the base plate 38. Rigidly secured to and depending from the central portion of the base plate 38 is a stud 46, and mounted to move vertically on this stud is a yielding lever abutment 47. A cap 48 is adjustably held in position by a nut 49 on the threaded lower end of said stud. A coiled spring 50 surrounds the stud 46, is fitted into an annular seat of the abutment 47 and reacts against said abutment and the base plate 38, exerting a yielding force tending to keep the abutment pressed downward. A pair of levers 51 is intermediately pivoted to lugs 52 depending from the base plate 38, and these lugs, at their inner ends, are pivoted in seats formed in the abutment 47, and at their outer ends, are pivoted in seats formed in the so-called cross heads 44.

Through the connections just described, the spring 50 exerts a force that will normally hold the tripping rod 41 at its opposite ends at the apexes of the two V-shaped cam slots, the upper surface of which cam slots work as cams on the said rod to normally hold the same in intermediate uppermost position. The two levers 51 cause equal depressions of the opposite ends of the tripping rod, when, for example, the wheel is run over the rod close to one end. The cam-acting arm 42, secured to the ends of the tripping rod cause the same to move simultaneously in the same direction down the V-shaped cam grooves and will prevent, for example, one end of the rod from starting down one side of one V-shaped cam slot and the other end of the rod from starting in the other direction down the other side of the other cam slot.

At one end, the tripping rod 41 of each tripping device works in the vertical slot 53 of a plunger head 54 that is rigidly secured to a plunger rod 55 mounted to slide endwise through depending flanges 39^a formed on the base plate 38 below the pockets 39. The rods 55 of the two tripping devices extend toward each other and toward the lever 37 of the controller valve, and at their extended ends, are provided with bifurcated heads 55^a, the prongs of which, as shown, are provided with pins 56 130

that work in slots 57 of connecting heads 58. These connecting heads 58, as shown, are rigidly secured to the ends of tubular spring casings 59 that are provided at their extended ends with caps 60. The numeral 61 indicates connecting rods pivoted at their inner ends to the opposite ends of the controller valve lever 37, and at the outer ends extend into the tubular spring casings 59 through the caps 60 thereof, and provided within said tubes with heads 62. Coiled springs 63 are located within the casing 59 and are compressed between the same and the heads 62 exerting force which normally causes the above noted elements 58, 59 and 61 to operate as single or integral elements, but in which the spring 63, under certain conditions, will yield and prevent breaking or bending of the parts.

20 The semaphore or signaling device may take various forms, but, as shown, comprises as follows:

The numeral 64 indicates a casing made up of laterally spaced plates rigidly secured to and depending from a bracket 65 that is rigidly secured in any suitable way to the wall of the building adjacent to the door opening. The numeral 66 indicates the semaphore blade which works between the plates of the casing 64 and is pivoted thereto at 67. For operating the semaphore plate we provide a small cylinder and piston air holder, the cylinder 68 of which is rigidly secured to the brackets 65 in an upright position. Working in the cylinder 68 is a piston 69, the stem 69^a of which works through a vertical extension 65^a of the bracket 65. The piston stem 69^a carries a laterally projecting stud 70 that is pivoted to the upper end of a link 71, the lower end of which link is pivoted to the semaphore blade 66 at 72, which point 72 is offset from the pivot 67. In the upper side portions of the cylinder 68 are air discharge ports 73.

45 As a feature of this invention, the exhaust pipe 28, which, in the arrangement illustrated, leads directly from the valve casing 29, and indirectly from the cylinder 20 of the door actuating air motor, is connected to the lower or compression end of the cylinder 68 of the semaphore actuating air motor. The cylinder 68 in its lower or compression end, is provided, however, with a constantly open but restricted exhaust passage 74.

Operation.

The operation of the mechanism described is as follows:

60 Figs. 2, 4 and 5 show the normal position of the parts of the tripping device and the full lines, Fig. 2, indicate the position of the valve actuating connections between the tripping devices and the controller valve

65 when the door is in an open or elevated posi-

tion. Fig. 9 shows an intermediate position of a valve actuating head 39 and arm 35 when the valve actuating lever 37 is midway between the two extreme positions indicated by full and dotted lines in Fig. 2. When 70 the said valve actuating lever 37 is in the position shown by full lines in Fig. 2, head 33 will be forced toward the right, in respect to Figs. 2 and 9, thereby causing spring 32 to positively close check valve 31 75 and thereby positively forcing air admission valve 30 into an open position. This adjustment of the valves 31 and 30 just stated, permits air, under pressure, from air supply pipe 26 to flow through the chamber of 80 valve casing 29, and through pipe 27 to cylinder 20 of the door actuating air motor, causing the door to be moved to an open position and there held in an open position as long as lever 37 stands in its full line 85 position Fig. 2.

It must be assumed that lever 37 is set in its full line position Fig. 2 while a vehicle wheel, or the like, passes in the one direction or the other over one or the other of the tripping rods 41, thereby depressing the said rod and forcing the same inward toward the door, and it should now be assumed that the vehicle is between the two tripping rods and will pass either into the 90 building over the inner rod or from the building over the outer rod, in either of which events the resulting action will be the same. Hence, assume that the vehicle passes outward over the left hand tripping rod 41 100 and thereby depresses the same and causes the ends of the rods to move down the left hand branch or against the left hand oblique cam surface of cam slot 40. When the tripping rod 41 is thus depressed, it will, because of the vertically moving pivots 43, be caused to oscillate in a direction which will force plunger head 54, and hence, the connected plunger 55 outward, or away from lever 37, and inasmuch as left hand pin 56 110 is at the beginning of such movement, at the outer extremity of the coöperating rod 57, it is evident that the outer or left hand connecting rod 61 will be moved outward or toward the left, thereby moving lever 37 to 115 the dotted line position Fig. 2. This movement of lever 37 from full line to dotted line position Fig. 2, moves valve actuating head 33 toward the left in respect to Fig. 9, thereby leaving admission valve 30 closed while 120 moving exhaust valve 31 to open position, thereby permitting the exhaust of air from cylinder 20 through pipe 27, through chamber of valve casing 29 and exhaust pipe 28. This permits the piston of cylinder 20 to return under the weight of the door and the door can be automatically closed with its preponderance of weight over that of the counter weight 16. It may be here noted that when left hand rod 61 is moved, as just 125 130

above stated, to set lever 37 from its full to its dotted line position Fig. 2, the right hand connecting rod 61 may also be moved but does not impart movement to the right hand thrust bolt 55 because, at the beginning of such movement, right hand pin 56 was at the right hand extremity of coöperating slot 57. However, when lever 37 is set in its dotted line position, right hand slot 57 will be set with its left hand extremity engaged with coöperating pin 56 and, moreover, as soon as the depressed left hand trip rod 41 is released, it is restored to its normal position, thereby setting left hand pin 56 at the right hand extremity of the coöperating slot 57. This then leaves the two connecting rods 61 and coöperating connections to the tripping devices so set that when either one of the trip rods 41 is depressed and moved toward the door and lever 37, such movement will set valve lever 37 from its dotted line position back into its full line position Fig. 2, thereby again causing the door to open. It is, of course, evident that when one of the rods 41 is depressed or moved away from the door, the coöperating plunger head 54 and plunger 55 will be given a movement in the same direction, and that when one of the said tripping rods is moved toward the door the said coöperating elements 54 and 55 will be given a movement in that same direction. Attention is also called to the fact that a second depression of either of the tripping rods 41 in the same direction has not been effected on the connecting rods 61 or valve lever 37, since the same will be then found already set by the first depression of the trip rod in the position in which they would be set by a second depression if the first depression had not already taken place.

The V-shape or reverse downward divergence of the so-called cam slots or surfaces 40 positively cause the upwardly spring pressed trip rods 41 to normally stand accurately in intermediate uppermost positions and positively prevent over movements or vibrations of the rods after they have once reached their normal intermediate uppermost positions.

We will now note the action of the exhaust on the semaphore. When the door is being opened or the door actuated air motor has just been set into action to open the door, there will, of course, be no exhaust through the exhaust pipe 28, and hence, the semaphore will not be operated nor is there any necessity that it should be since there is no danger that can result from opening of the door. When, however, the door is descending or closing or released for such movement, by exhaust from air from the cylinder 20, there is a danger that the door might close on a person or upon a vehicle moving either into or out of a building, and

at such time, the semaphore will be thrown up in the dotted line position Fig. 1 and full line position Fig. 7, by the exhaust acting as follows: Exhaust air from cylinder 20, passing through pipe 27 valve casing 29 and exhaust pipe 28 will enter cylinder 68 and will begin to slowly leak through contracted exhaust port 76 but cannot escape through such exhaust port fast enough to prevent sufficient pressure in cylinder 68 to cause piston 69 to be raised, thereby throwing the semaphore into its horizontal position. When piston 69 moves above exhaust perforations 73, its further upward movement will be stopped. The semaphore will then be held in its projected position until the door has been completely closed, and then the said semaphore will, under its own gravity and the weight of piston 69, be slowly restored to normal retracted position as the air caged in cylinder 89 escapes through restricted exhaust port 74. The semaphore is, therefore, in a very advantageous way, operated by the exhaust from the door actuating air motor. The door closing and semaphore signaling movements are properly and accurately timed, the one in respect to the other.

The efficiency and practicability of the door actuating mechanism herein described has been demonstrated in actual usage.

What we claim is:

1. The combination with a movable door, or the like, of a cylinder and piston air motor, the piston thereof having a connection to said door for operating the same, a valve casing, a pipe connecting said valve casing to the cylinder of said air motor, a compressed air supply pipe extending to said valve casing and provided with an admission valve, a pipe extending from said casing and provided with an exhaust valve, a valve actuating head in said valve casing operative when moved in one direction, to close said exhaust valve and open said admission valve, and when moved in the other direction to open said exhaust valve and permit said admission valve to close, and connections for operating said valve actuating mechanism and including a trip for the driveway.

2. The combination with a movable door, or the like, of a cylinder and piston air motor, the piston thereof having a connection to said door for operating the same, a valve casing, a pipe connecting said valve casing to the cylinder of said air motor, a compressed air supply pipe extending to said valve casing and provided with an admission valve, a pipe extending from said casing and provided with an exhaust valve, a valve actuating head in said valve casing operative when moved in one direction, to close said exhaust valve and open said admission valve, and when moved in the other

direction to open said exhaust valve and permit said admission valve to close, a crank with connections for reciprocating said valve actuating head, a double-ended lever connected to said crank and tripping devices in the driveway having independent connections to the opposite ends of said lever.

3. The combination with a movable door, or the like, of a cylinder and piston air motor, the piston thereof having a connection to said door for operating the same, a valve casing, a pipe connecting said valve casing to the cylinder of said air motor, a compressed air supply pipe extending to said valve casing and provided with an admission valve, a pipe extending from said casing and provided with an exhaust valve, a valve actuating head in said valve casing operative when moved in one direction, to close said exhaust valve and open said admission valve, and when moved in the other direction to open said exhaust valve and permit said admission valve to close, a crank with connections for reciprocating said valve actuating head, a double-ended lever connected to said crank and tripping devices in the driveway having independent connections to the opposite ends of said lever, the said connections having slip motion devices for the purposes set forth.

4. The combination with a movable door, or the like, of a door actuating mechanism comprising an air motor, a controlling valve therefor, a valve actuator including a trip in the driveway, and a semaphore operated by exhaust of air from said air motor.

5. The combination with a movable door, or the like, of a cylinder and piston air motor, the piston thereof having a connection to said door for operating the same, a valve casing, a pipe connecting said valve casing to the cylinder of said air motor, a compressed air supply pipe extending to said valve casing and provided with an admission valve, a pipe extending from said casing and provided with an exhaust valve, and vehicle actuated means for operating said admission and exhaust valves in reverse order to effect the opening and closing of said door, a semaphore, a cylinder and piston air motor for operating said semaphore, the cylinder of said latter motor being con-

nected to said exhaust pipe from said valve casing.

6. The combination with a movable door, or the like, of a cylinder and piston air motor, the piston thereof having a connection to said door for operating the same, a valve casing, a pipe connecting said valve casing to the cylinder of said air motor, a compressed air supply pipe extending to said valve casing and provided with an admission valve, a pipe extending from said casing and provided with an exhaust valve, and vehicle actuated means for operating said admission and exhaust valves in reverse order to effect the opening and closing of said door, a semaphore, a cylinder and piston air motor for operating said semaphore, the cylinder of said latter motor being connected to said exhaust pipe from said valve casing, the said cylinder having a restricted normally open exhaust passage.

7. In an actuating mechanism for doors, or the like, a tripping mechanism comprising laterally spaced members having approximately V-shaped cam surfaces, a tripping rod working against said V-shaped cam surfaces and normally yieldingly pressed upward into the apexes of said camways, connecting rods for controlling the door movements, and means whereby depression of said tripping rod, operating through said rods, will control the door movements.

8. In an actuating mechanism for doors, or the like, a tripping mechanism comprising raised bars with approximately V-shaped cam channels, a trip rod working in alined cam channels, yielding means pressing said tripping rod upward into the apexes of said channels, connecting rods for controlling the door movements and means whereby depression of said tripping rod will impart endwise movements to said connecting rod.

In testimony whereof we affix our signatures in presence of two witnesses.
